CLAIM

The ornamental design for a bed rail, as shown and described.

DESCRIPTION

FIG. 1 is a front perspective view of a bed rail, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front perspective view, showing the bed rail in an alternate condition of use.

The bed rail is shown with a symbolic break. The appearance of any portion of the article between the break lines forms no part of the claimed design.
